Attorney

UNITED STATES PATENT OFFICE.

EDWARD FRANKLIN BRAUCHER, OF DENVER, COLORADO.

ADVERTISING DISK FOR AUTOMOBILE WHEELS.

Application filed February 9, 1924. Serial No. 691,643.

To all whom it may concern:

Be it known that I, EDWARD FRANKLIN BRAUCHER, a citizen of the United States, residing at Denver, the city and county of Denver and State of Colorado, have invented certain new and useful Improvements in Advertising Disks for Automobile Wheels; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to advertising devices and has special reference to improvements in advertising disks of the type disclosed and claimed by me in Patent No. 20 1,432,274, granted to me on October 17, 1922.

It is the object of this invention to produce a disk that can be readily applied to an automobile wheel and which will be provided with its own bearing member that can 25 be screwed onto the wheel in the place of the ordinary cap.

It is a further object to produce an advertising disk that shall rotate on ball and roller bearings, and which shall have a neat 30 and ornamental appearance.

My invention can be best described and will be most readily understood when reference is had to the accompanying drawing in which the preferred embodiment thereof is shown, and in which:

Fig. 1 is a side elevation showing my improved disk in place on the front wheel of an automobile;

Fig. 2 is a section taken on line 2—2, 40 Fig. 1; and

Fig. 3 is a view of the inner surface of the disk taken on line 3—3, Fig. 2.

Numeral 1 represents the pneumatic tire of an automobile wheel and 2 represents 45 the outer end of the hub, which is threaded as indicated at 3, while 4 indicates the spokes of the wheel. In place of the ordinary hub cap, I provide a special cap which is indicated as a whole by the numeral 5. This 50 cap has an interiorly threaded portion that cooperates with the threaded portion 3 of the hub. The cap has such length that when it is screwed onto the hub, its end engages or almost engages the hub plate 6. The 55 outer end of the cap has a non-circular portion 7 that can be engaged by a wrench

for applying the cap to the wheel or for removing it therefrom. The extreme outer end 8 of the cap 5 is of greatly reduced diameter and is threaded for the reception 60 of a nut 9, by means of which the inner ball raceway 10 is clamped against the shoulder 11. The outer surface of the cap 5 is cylindrical and is preferably machined so as to be concentric with the threaded opening. 65 My advertising device comprises a disk 12 whose outer edge is rolled about a wire in the manner indicated at 13. This disk has a central opening of sufficient size to receive the inner end of cap 5. Secured to 70 the outside of the disk 12 and concentric with the opening therein is a conical housing 14 which is provided at its larger end with a flange 15, which is fastened to the disk by means of rivets 16. Near the outer 75 end of the housing is a transverse wall 17 which has a central opening for the reception of the ball raceway 18. Mounted for rotation between lugs 19 and the outside of the disk are three rollers 20 which are so 80 spaced that they will admit the cap 5 between them. The end of the casing projects beyond the wall 17, as indicated at 21, and is externally threaded for the reception of a cap 22, which closes the outer end of 85 the casing and conceals the nut 9 which may be held from removal by means of a split pin in the usual way. To the inside of the disk, I secure a heavy piece of metal 23 that serves to keep the disk from rotating. A 90 brace 24 may connect the casing 14 and the lower side of the disk when this is found to be desirable.

In order to enable the air hose to be connected to the air valve from the outside of 95 the wheel in the usual way, I provide the disk with an opening 25 provided with a cover 26.

Since my disk is provided with rollers 20 that roll on the outside of the hub cap 100 and since it has a ball bearing composed of raceways 10 and 18, one (10) of which is clamped to the cap and the other (18) of which is secured in an opening in wall 17, it is apparent that the disk and cap can 105 rotate freely on each other. As the wheel rotates, the weight 23 will keep the disk from rotating with the result that it will have no rotary, but only a motion of lineal translation with respect to the ground, so 110 that any sign that is painted on the disk can be read while the machine to which it

is secured is traveling. A felt washer 27 may be placed between the disk and the hub plate 6 when it is found desirable to do so. This washer prevents dust and dirt from entering within casing 14. It is my intention to place grease within the casing so that the rollers and the ball bearing will be properly lubricated.

My disk in addition to serving as an advertising medium, serves to beautify the car by presenting a smooth varnished surface to the view of the observer and it hides the otherwise dirty wheel. My disk also shades the wheel and thereby prevents the shrinkage of the wooden spokes and felloe that otherwise occurs. It permits the tire to be readily removed and chains to be put into place thereon. When driving in the mud, the disk protects the wheel and is easily kept clean, even in muddy, rainy weather, as the mud drips off the smooth surface or can be quickly removed by means of a hose.

On Sundays or other times when the car is to be used for pleasure only, the disks 25 can be removed. Owing to the double spaced bearings, the disk will not wobble but will hang straight and smooth.

Having now described my invention, what I claim as new is:

1. An advertising disk adapted to be applied to a revolving wheel having an outwardly projecting hub portion, a cap adapted to be secured to the outside of the hub, said cap having at its outer end a portion of 35 reduced diameter, said portion being threaded for the reception of a nut, a ball-bearing secured to said portion of reduced diameter,

a disk, a conical housing secured thereto, a plurality of rollers connected to the disk and the housing, said housing having a 40 transverse wall near its outer end, said wall having an opening for the reception of the ball-bearing and a threaded cap to close the outer end of the housing.

2. An advertising disk adapted to be applied to an automobile wheel, said disk being circular and provided with a central opening, a conical housing secured to the disk, said housing having a transverse wall near its outer end, an opening in said wall 50 for the reception of a ball-bearing, a plurality of rollers secured to said housing and disk, and a threaded cover secured to the outer end of the housing.

3. An advertising device adapted to be secured to the hub of an automobile wheel comprising, in combination, a cylindrical cap adapted to be threaded onto the hub, the outer surface of said cap being concentric with the threaded surface thereof, said cap having an axially extending portion of reduced diameter, said portion being threaded for the reception of a nut, a ball race on said reduced portion, a disk having a conical housing secured thereto, a ball race carried by the housing and adapted to cooperate with the ball race on the reduced portion, and spaced rollers connected to said housing and to said disk, said rollers being adapted to rotate and to cooperate with the 60 outer surface of the cap.

In testimony whereof I affix my signature.

EDWARD FRANKLIN BRAUCHER.
